CLAIM

The ornamental design for a light, as shown and described above.

DESCRIPTION

FIG. 1 is a front perspective view of a light of the present invention;

FIG. 2 is a front elevation view of the light shown in FIG. 1;

FIG. 3 is a rear elevation view of the light shown in FIG. 1;

FIG. 4 is a right-side view of the light shown in FIG. 1;

FIG. 5 is a left-side view of the light shown in FIG. 1;

FIG. 6 is a top view of the light shown in FIG. 1;

FIG. 7 is a bottom view of the light shown in FIG. 1;

FIG. 8 is a rear perspective view of the light shown in FIG. 1;

FIG. 9 is a front perspective view of a second exemplary light of the present invention;

FIG. 10 is a front elevation view of the light shown in FIG. 9;

FIG. 11 is a rear elevation view of the light shown in FIG. 9;

FIG. 12 is a right-side view of the light shown in FIG. 9;

FIG. 13 is a left-side view of the light shown in FIG. 9;

FIG. 14 is a top view of the light shown in FIG. 9;

FIG. 15 is a bottom view of the light shown in FIG. 9; and,

FIG. 16 is a rear perspective view of the light shown in FIG. 9.

The broken lines shown in the drawings illustrate environmental structure and form no part of the claimed design. The Light has been shown with break lines in its length. The appearance of any portion of the article between the break lines forms no part of the claimed design.

1 Claim, 10 Drawing Sheets
